UNITED STATES PATENT OFFICE.

HENRY HELLWEG, OF MILWAUKEE, WISCONSIN, ASSIGNOR TO HELZEN CORPORATION,
OF MILWAUKEE, WISCONSIN, A CORPORATION OF WISCONSIN.

CAR HEATER.

Application filed January 17, 1924. Serial No. 686,893.

This invention relates to heaters which utilize the heat of the exhaust gases from automobile engines to heat air for warming the interior of automobiles in cold weather.

The main objects of the invention are to provide a heater which can be easily installed in place of the usual exhaust manifold with which a car, such as a Ford car, is equipped, which will take in and effectively heat fresh air and deliver it under regulated control into the car; to prevent leakage of exhaust gas or admission of dust into the air-heating space of the heater and its delivery therefrom into the car; to provide against over-heating the exhaust manifold, particularly in connection with a hot-spot intake manifold and thus prevent warped engine valves, reduce back pressure on the engine, deposit of carbon and consumption of fuel and cause the engine to run smoother; to provide not only for better regulation of the heated air admitted into the car, but also of the heating of the manifold itself; and generally to improve the construction and operation of heaters of this class.

The invention consists in the construction, arrangement and combination of parts as hereinafter particularly described and pointed out in the claims.

In the accompanying drawing like characters designate the same parts in the several figures.

Figure 1 is a side elevation of a heater embodying the invention as applied to an automobile engine, such as the engine of a Ford car; Fig. 2 is a plan view of the heater and a part of the engine to which it is applied; Fig. 3 is an enlarged cross section of the heater on the line 3—3, Fig. 1; Fig. 4 is a partial cross section on the line 4—4, Fig. 1; Fig. 5 is a sectional detail view of a detent for holding the valves at the rear end of the heater in adjusted position; Fig. 6 is an enlarged vertical longitudinal section of the heater on the line 6—6, Figs. 3 and 7; Fig. 7 is a horizontal section of the heater on the line 7—7, Figs. 3 and 6; and Fig. 8 is a vertical longitudinal section on the line 8—8, Figs. 3, 4 and 7.

The heater as constructed for a four-cylinder internal combustion engine such as the engine of a Ford car, comprises an exhaust manifold having a longitudinal exhaust gas

2, formed on opposite sides thereof by side walls 3 and 4, cast or formed integrally with top and bottom walls 5 and 6.

On the under side the exhaust manifold and heater is formed integrally with downwardly and laterally extending branches 8, for connection with the exhaust ports of the engine, in the usual or any suitable manner.

At its rear end the gas passage 1 is extended in a downwardly and rearwardly inclined neck 10, which is threaded for connection therewith of an exhaust pipe leading to the muffler.

At the front and rear ends of the manifold and heater the passages 2 are extended and communicate with each other beyond the ends of the gas passage 1. At the front end the heater is provided with a flaring mouth or air intake 12, which is located behind and adjacent to the fan 13, as shown in Figs. 1 and 2, in communication with the front ends of the passages 2. This mouth or intake is preferably cast or formed separate from the manifold and heater, and is fastened thereto by screws 14, as shown in Figs. 6, 7 and 8.

At their rear ends the passages 2 open into a register box and valve case 16, which is formed with openings in its upper and lower sides for the delivery or discharge of heated air into or outside of a car. This box or case is preferably cast or formed separate from the body of the manifold and heater, and is fastened thereto, as shown in Figs. 1, 2 and 7, by outwardly projecting flanges 90 or ears and screws 17. The upper wall 18 of the box or case 16 is inclined downwardly and rearwardly, as shown in Figs. 1, 6 and 8, to correspond with the inclination of the footboard 19, into an opening in which it is fitted, as shown in Fig. 1. The downwardly inclined wall 18 in which openings are made for delivering heated air into the car, forms a grate, as shown in Fig. 2.

Two independently operable dampers or leaf valves 21 and 22 are pivotally mounted in the rear end of the box or case 16 on parallel horizontal pins 23, having bearings in the side walls of the box or case, as shown in Figs. 6, 7 and 8. Each pin 23 is extended at one end beyond the side of the box or case, and provided with an operating lever or arm 24, the upper end of which is preferably extended and serrated as shown, to facilitate its operation by foot. These op-

- erating levers or arms 24 are located on opposite sides of the box or case 16, so that they can be easily operated independently of each other for separately adjusting the 5 damps or valves 21 and 22. Each lever or arm 24 is provided with a detent for holding it and the damper or valve with which it is connected, in adjusted position. This 10 detent preferably consists as shown in Fig. 5, of a ball 26, loosely confined in a transverse socket 27, formed in the extended lower end of the lever or arm 24 and yieldingly pressed and held by a spring 28 against the adjacent side wall of the box or case 16, 15 which may if desired, be formed at suitable intervals in the path of the ball, with shallow depressions or seats to hold the damper or valve in different positions to which it may be adjusted.
- 20 The walls 4 of the exhaust gas passage 1 are, preferably formed with longitudinal heat radiating ribs or wings 30, projecting therefrom into the air passages 2.
- A hot-spot intake manifold 32 is preferably cast or formed integrally with the 25 exhaust manifold and heater, so that the cooling effect of the air flowing through the passages 2 on the adjoining parts of the manifolds, particularly in hot or warm 30 weather, will prevent overheating of the intake manifold 32, and thereby reduce the consumption of fuel, and cause the engine to run smoother and with greater efficiency.
- The intake manifold is formed with upwardly and laterally projecting branches 33, 35 which are joined integrally with the lower wall 6 of the exhaust manifold and heater, thus providing so called hot-spots for imparting heat to the fuel gas or mixture as it is supplied to the engine cylinder, the 40 branches of the intake manifold being connected in the usual or any suitable manner with the admission ports of the engine.
- The upper wall of the intake manifold 32 45 is integrally joined with the intermediate downwardly extending branches 8 of the exhaust manifold, thereby providing additional hot-spots for heating the fuel gas or mixture on its way to the branches 33 and thence to the inlet ports of the engine cylinders.
- The manifolds and heater are detachably fastened to the cylinders or cylinder block 50 of an engine 35, as shown in Fig. 1, by clamps 36 having seats 37 on the outer sides of the manifold branches 8 and 33 and connected between their ends with the cylinders or cylinder block by bolts 38.
- In the operation of the heater, when the 60 engine with which it is connected is running and either or both valves 21 and 22 is open, air is forced by the fan 13 into the flaring mouth or intake 12 and forced by the fan 13 through the passages 2 in contact with 65 the walls 4 and the heat radiating ribs or

wings 30, from which it absorbs heat produced by the exhaust gases from the engine flowing through the passage 1. If both valves 21 and 22 are turned down, as shown in Fig. 6 and indicated by dotted lines in 70 Fig. 1, the heated air will be discharged freely through the register box 16 and the grate 18 on the upper side thereof, into the car.

In hot weather both valves 21 and 22 may 75 be turned up, as shown in Fig. 8, so as to close the openings through the grate 18 and direct all the heated air discharged from the passages 2 downwardly through the opening in the under side of the register 80 box 16 below the floor of the car.

In moderate or cool weather, the valves may be adjusted to different positions so as to direct a part only of the heated air from the passages 2 through the grate 18 into 85 the car, or to direct a part only through the opening in the under side of the register box 16, as by completely closing one valve and partially closing or opening the other.

To quickly warm up the engine for start- 90 ing, particularly in cold weather, both valves 21 and 22 may be closed, so as to prevent the flow of air through the passages 2 and confine all the heat developed by the exhaust gases in their passage through the heater between the walls 3 and 4, and utilize it to the fullest extent for heating the fuel gas or mixture supplied to the engine through the branches 33 of the hot-spot intake manifold 32.

When the engine is warmed up and started, the valves are set to discharge all or a part of the air heated in the passages 2 through the grate or openings in the upper side or through the opening in the under side 105 of the register box 16, or partly through the upper and partly through the lower opening, according to temperature conditions.

In warm or hot weather, when both valves are turned up, as shown in Fig. 8, the forced 110 draft of fresh air through the passages 2 will rapidly take up and carry off the heat imparted by the exhaust gases from the engine to the walls 4 and the adjoining branches 8 and 33 of the exhaust and intake 115 manifolds, thereby preventing the over-heating of the intake manifold and undue expansion and rarefaction of the fuel gas or mixture without affecting the advantage derived from the use of the hot-spot manifold under other conditions, as for heating the fuel gas or mixture in warming up and starting the engine, or for running in cold weather.

Various modifications in the construction 125 and arrangement of parts of the device may be made without departure from the principle and scope of the invention as defined in the following claims.

I claim:

1. A device of the character described comprising an exhaust manifold having a longitudinal exhaust gas passage and an air-heating passage adjoining the exhaust gas passage and having an intake at the front end and an outlet at the rear end to provide for the flow of air through said device in a direction longitudinally thereof, means for controlling the flow of air through said heating passage, and an intake manifold formed integrally with the exhaust manifold which is adapted to impart heat by conduction to the fuel supplied through the intake manifold to an engine modified by air flowing through the air-heating passage, said air-heating passage being partitioned from and out of communication with said exhaust and intake manifolds.

2. A device of the character described comprising an exhaust manifold having a longitudinal exhaust-gas passage provided with depending branches, an intake manifold having branches joined integrally to the lower wall of the exhaust-gas passage, the upper wall of the intake manifold being joined integrally to intermediate branches of the exhaust manifold, an air heating passage adjacent the hot-spot connections between the exhaust and intake manifolds, said air passage being partitioned from both the exhaust-gas passage and the intake manifold and providing for the flow of air through said device in a direction longitudinally thereof, and means for controlling the flow of air through the air heating passage whereby overheating of the fuel gas or mixture flowing through the intake manifold may be prevented.

3. In a device of the character described, a casing comprising top, bottom, and side walls, partitions arranged intermediate said side walls and in spaced relation with respect thereto to provide an exhaust manifold extending longitudinally of said casing and air-heating passages at each side of said exhaust manifold, means adapted to connect said exhaust manifold to the exhaust ports of an internal combustion engine, said device being provided with an intake manifold associated with said exhaust manifold whereby exchange of heat between said manifolds is readily effected, and means associated with said air-heating passages and adapted and arranged to control the flow of air through the latter and the rate of the exchange of heat between said manifolds.

4. In a device of the character described, a casing comprising top, bottom, and side walls, partitions cast integrally with said

top and bottom walls and arranged intermediate said side walls and in spaced relation with respect thereto to provide an exhaust manifold extending longitudinally of said casing and air-heating passages at each side of said exhaust manifold, means adapted to connect said exhaust manifold to the exhaust ports of an internal combustion engine, said device being provided with an intake manifold associated with said exhaust manifold whereby exchange of heat between said manifolds is readily effected, and means associated with said air-heating passages and adapted and arranged to control the flow of air through the latter and the rate of the exchange of heat between said manifolds.

5. In a device of the character described, a casing comprising top, bottom, and side walls, partitions cast integrally with said top and bottom walls and arranged intermediate said side walls and in spaced relation with respect thereto to provide an exhaust manifold extending longitudinally of said casing and air-heating passages at each side of said exhaust manifold, said partitions being provided with heat-radiating ribs extending laterally with respect thereto and into said air-heating passages, means adapted to connect said exhaust manifold to the exhaust ports of an internal combustion engine, said device being provided with an intake manifold associated with said exhaust manifold whereby exchange of heat between said manifolds is readily effected, and means associated with said air-heating passages and adapted and arranged to control the flow of air through the latter and the rate of the exchange of heat between said manifolds.

6. In a device of the character described, a casing provided with an exhaust passage extending longitudinally thereof, an intake manifold associated with said casing, and an exhaust conduit communicating with said exhaust passage, said manifold and said conduit having a common heat-conducting wall whereby said wall permits ready transfer of heat from said conduit to said manifold, said casing being further provided with an air passage extending longitudinally thereof and being partitioned from both said exhaust passage, and said intake manifold, said air passage being in direct communication with the atmosphere at each end thereof to permit cooling air to flow longitudinally through said casing and past said exhaust passage.

In witness whereof I hereto affix my signature.

HENRY HELLWEG.
